UNITED STATES PATENT OFFICE

JOHN N. RAY, OF NEWARK, NEW JERSEY, ASSIGNOR TO BRANDES LABORATORIES, INC.,
OF NEWARK, NEW JERSEY, A CORPORATION OF NEW JERSEY

ELECTRICAL PHONOGRAPH APPARATUS

Application filed January 29, 1927. Serial No. 164,549.

My invention relates broadly to electrical pick-up devices for phonographs and more particularly to a novel construction of electromagnetic pick-up device for electric phonographs.

One of the objects of my invention is to provide an electromagnetic pick-up device by which records of the hill and dale construction or of the laterally cut construction may be played by use of the same pick-up device.

Another object of my invention is to provide a construction of electric pick-up for phonographs which is readily convertible for either hill and dale records or laterally cut records by a simple shift of the electromagnetic mechanism through an angular distance of approximately 90 degrees.

Still another object of my invention is to provide a simplified construction of an electromagnetic pick-up for phonographs embodying a minimum number of parts associated within a compact space with a central armature member movable within a permanent magnetic field and concentrically disposed within a winding in which variable currents may be induced in accordance with the movement of the armature under control of a stylus for the development of currents in the winding in accordance with a phonograph sound record.

A further object of my invention is to provide an arrangement for mounting a rockable armature member concentrically within a system of permanent magnets and within an electromagnetic winding wherein variable currents may be induced in accordance with the motion of the stylus under control of a phonograph sound record where the armature member may be shifted in position through an angular distance for adapting the stylus to both the hill and dale record and the laterally cut type of record without further change in the equipment.

My invention will be more clearly understood from the specification hereinafter following by reference to the accompanying drawings in which:

Figure 1 is a fragmentary view of an electric phonograph showing the electric pick-up device of my invention mounted with re-

spect to a phonograph record; Fig. 2 is an enlarged cross-sectional view taken through the phonograph pick-up device of my invention; Fig. 3 is a cross-sectional view on line 3—3 of the phonograph pick-up illustrated in Fig. 2; Fig. 4 is a lateral cross-sectional view through the phonograph pick-up device taken on line 4—4 of Fig. 3; Fig. 5 is a cross-sectional view through the electromagnetic pick-up device on line 5—5 of Fig. 3; Fig. 6 is a cross-sectional view taken through the phonograph pick-up device on line 6—6 of Fig. 3; Fig. 7 shows the position of the electromagnetic pick-up mechanism for reproduction with respect to laterally cut phonograph records as illustrated diagrammatically in Fig. 7a; Fig. 8 is a view of the phonograph pick-up device shifted in a position for operation by a hill and dale phonograph record as illustrated diagrammatically at Fig. 8a; Figs. 9 and 10 show views of the armature member employed in the phonograph pick-up device; and Figs. 11, 12 and 13 are views of a modified construction of the phonograph pick-up device of my invention.

The magnetic pick-up illustrated herein is intended for operation with an amplifier system and loud speaker for the reproduction of phonograph records electrically. The device of my invention is essentially a generator, the magnetic field being supplied by a permanent magnet which corresponds to the field coils of a generator. I provide a pair of pole angles for concentrating the flux supplied by the permanent magnet. An armature is arranged between the pole pieces with a coil disposed around the armature. The armature provides a socket in which a stylus is carried and the movement of the armature effects a cutting of the magnetic lines of force thereby inducing a voltage in the winding. The current is amplified through an electron tube system and utilized to operate a loud speaker for the reproduction of sound in accordance with the movement of a stylus under control of the phonograph record.

My invention will be more clearly understood by reference to the accompanying drawings in which the phonograph cabinet

has been designated by reference character 1 with a record table positioned thereon and a sound record 3 carried by the record table 2. The phonograph tone arm is illustrated 5 at 4 with a telescopic extension 5 thereon into which a tubular member 6 may be inserted for establishing connections with contacts within the tone arm which lead to the input of the amplifier circuit. The phonograph 10 pick-up is positioned within a casing 7 normally disposed at an angle with respect to the tubular member 6 as represented in the drawings. The tubular portion 8 of the phonograph pick-up is integrally connected 15 with the tubular portion 6 and carries a circular plate member 9 to which the body portion of the pick-up is movably connected. The body portion of the pick-up device is carried by a circular plate member 10 which 20 is journaled in an aperture in the circular plate member 9 of the pick-up and confined therein by means of a nut or other suitable securing means 11. An arcuate slot 25 is provided in the plate member 10 into which 25 a pin 26 secured to the plate member 9 projects for permitting the angular movement of the body portion of the electromagnetic phonograph pick-up device. A permanent magnet 12 is supported from the plate member 10 by means of screws 20 and 21. 30 Pole angles 14 and 15 are secured to the permanent magnet structure by means of screws 16 and 17. The pole angles 14 and 15 face toward each other and grip between their 35 faces an armature member 30 with a resilient tubular mounting represented at 34. Surrounding the armature member 30 I provide an insulated coil support 29 on which a winding 28 is disposed concentric with the 40 central portion of the armature 30. Conductors extend from the winding 28 through the plate 10 and the aperture 29 in the plate member 9 and connect to contact members 43 carried in plug 42 adjustable by means of 45 screw member 44 in the tone arm 5. The head of the tubular portion 8 is normally closed by means of a cap screw 24.

The armature member 30 has been more clearly illustrated in Figs. 9 and 10 as consisting of a central cylindrical portion flattened at 38 and provided with a laterally extending shoulder 39 with a flattened web portion 37 extending therefrom. The shoulder 39 provides the pivot upon which 55 the armature 30 moves and is also the center of gravity of the armature when the stylus 36 and actuating member 40 are in place. By virtue of the balancing of the armature on the shoulder 39 as a pivot, I have found 60 that greater volume of sound may be reproduced and higher frequencies more efficiently reproduced. A resilient lining 34 is provided in the oppositely disposed faces of the pole pieces 14 and 15 between which the 65 shoulder 39 of the armature 30 may freely

rock. The end 38 of the armature 30 is confined between tensioning or damping pads 33, the pressure on which is regulated by means of angle members 31 and 32 which are radially adjustable by means of screw members 45 and 46 fitting through elongated slots formed in the angle members 31 and 32. The resilient material 34 and 33 may be rubber or other soft or damping material which controls the movement of the armature member 30. A casing 41 is inserted over the phonograph pick-up device forming a housing for the apparatus, the casing being secured in place by means of screw members 18 and 19. The stylus 36 is inserted in the 80 portion 37 of the rockable armature and then the actuator 40 passed through the casing 41 and into the portion 37 of the armature member.

For playing laterally cut records as represented in Fig. 7^a the armature member is shifted to position represented in Fig. 7. For playing hill and dale records as represented in Fig. 8^a the armature member is shifted to a position represented in Fig. 8. 85

In Figs. 11, 12 and 13 I have represented a modified construction of the phonograph pick-up where the permanent magnet is in the form of a horse-shoe and is not entirely closed upon itself. 90

The pole angles 14 and 15 are so shaped in their adjacent faces with grooves therein that the armature member 30 may have its shoulder 37 gripped therein for allowing a rocking movement without the necessity of employing mechanical pivots thereby eliminating the question of maintenance to a large degree which might otherwise be necessary from time to time. 95

While I have described my invention in certain preferred embodiments, I desire that it be understood that modifications may be made and that no limitations upon my invention are intended other than are imposed by the scope of the appended claims. 105

What I claim as new and desire to secure by Letters Patent of the United States is as follows:

1. An electric pick-up for phonographs comprising a supporting member, an electromagnetic actuating system, an axially shiftable carrier for said electromagnetic system concentrically disposed on said supporting member, an armature member mounted with respect to said electromagnetic actuating system, a stylus carried by said armature member, said carrier being shiftable to one or another limiting positions over a displacement of substantially ninety degrees while maintaining the concentric relation between said carrier and said supporting member. 115

2. An electrical pick-up for phonographs comprising a supporting member, a rotatable carrier concentrically mounted upon said supporting member, an electromagnetic driver 120

- carried by said supporting member, an armature arranged to be actuated by said electromagnetic driver, a stylus in said armature, said carrier being shiftable to a selected one of either of two positions concentric with said supporting member, whereby movement of said stylus effected by either a hill and dale or a laterally cut phonograph record may impart a rocking movement to said armature.
3. An electrical pick-up for phonographs comprising a supporting arm, a carrier disposed in said arm, an angularly movable frame concentrically positioned on said carrier, a permanent magnet system supported on said frame, a pair of pole pieces secured to said permanent magnet system, an electromagnetic winding positioned adjacent said permanent magnet system, an armature member positioned between said pole pieces, a stylus carried by said armature member for imparting rocking movement to said armature member in accordance with a sound record, said magnet system and armature member being movable laterally through an angular distance of approximately ninety degrees by a change in position of said frame with respect to said carrier.
4. An electrical phonograph pick-up device comprising a supporting member arranged to be inserted in the tone arm of a phonograph, a rotatable carrier journaled upon said supporting member and arranged to move concentrically with respect to said supporting member, an electromagnetic operating mechanism supported on said rotatable carrier electromagnetic operating mechanism carrying a stylus by which mechanical vibrations may be imparted thereto, said electromagnetic operating mechanism and said stylus being shiftable in position concentric with said supporting member through an arc of approximately ninety degrees for imparting movement to said stylus from a sound record.
5. An electrical phonograph pick-up device comprising a tubular member arranged to be inserted in the tone arm of a phonograph, a bearing plate member integrally connected with said tubular member, a rotatable carrier journaled in a central position on said bearing plate member, said rotatable carrier supporting a permanent magnet system, a pair of pole pieces connected with said permanent magnet system, an electromagnetic winding positioned within said permanent magnet system, an armature member rockably mounted concentrically within said aforementioned electromagnetic winding, a stylus carried by said armature member, said permanent magnet system, electromagnetic winding, armature and stylus being shiftable through an angle of approximately ninety degrees by movement of said rotatable carrier concentrically with respect to said bearing plate member.
6. An electrical phonograph pick-up device comprising a tubular supporting member arranged to be inserted in the tone arm of a phonograph, a bearing plate member connected with said supporting member, a rotatable carrier journaled in a central position on said bearing plate member, electromagnetic means supported by said rotatable carrier, a rockable armature member mounted concentrically within said carrier and having a stylus connected thereto whereby mechanical vibrations may be imparted to said armature member for correspondingly moving said armature member within said electromagnetic means when said carrier is shifted in a position concentric with said carrier in either of two extreme positions for actuation by either a hill and dale or a laterally cut phonograph record.
7. An electrical phonograph pick-up device, comprising a member arranged to be connected with the tone arm of a phonograph, a bearing plate connected with said member, a rotatable plate journaled in said bearing plate and shiftable to either of two extreme positions, a permanent magnet system carried by said rotatable plate a pair of pole pieces secured to said permanent magnet system and directed toward each other, an electromagnetic winding located between said pole pieces, an armature disposed between said pole pieces and within said electromagnetic winding and vibratile therein by means of a stylus secured thereto said armature being resiliently mounted between said pole pieces and having means adjacent one end thereof for damping the vibration of said armature when said rotatable plate is shifted to either extreme position for actuation of said stylus by either a hill and dale or a laterally cut phonograph record.
8. An electrical phonograph pick up device comprising a member arranged to be connected with the tone arm of a phonograph, a bearing plate connected with said member, a rotatable plate journaled in said bearing plate and shiftable to either of two extreme positions, a permanent magnet system carried by said rotatable plate, a pair of pole pieces secured to said permanent magnet system and directed toward each other, an electromagnetic winding located between said pole pieces, an armature member resiliently mounted in the oppositely directed faces of said pole pieces and extending through said electromagnetic winding and limited in its movement by damping means at one end thereof and actuated at the other end thereof by means of a stylus when said rotatable plate is shifted to either extreme position for actuation of said stylus by either a hill and dale or a laterally cut phonograph record.
9. In an electrical phonograph pick up de-

vice, a supporting arm, a bearing plate carried by said arm, a frame angularly shiftable on said bearing plate to either of two extreme positions, an electromagnetic operating mechanism carried by said frame and comprising a permanent magnet system, a pair of pole pieces connected thereto and directed toward each other, an electromagnetic winding disposed between said pole pieces, an armature member centrally located within said electromagnetic winding, said armature member having a longitudinally extending shoulder thereon with resilient means for gripping said armature member at said shoulder between said pole pieces, a stylus carried by one end of said armature member and damping means for limiting the movement of the opposite end of said armature member when said frame is shifted to either extreme position for actuation of said stylus by either a hill and dale or a laterally cut phonograph record.

10. In an electrical phonograph pick-up device, a supporting member, a carrier shiftable to either of two extreme positions on said member, a permanent magnet system supported by said carrier, a pair of pole pieces connected with said permanent magnet system and directed toward each other, an electromagnetic winding disposed between said pole pieces, an armature member, said armature member comprising a T shaped magnetic device flattened at opposite ends, said armature device having its T shaped end resiliently mounted between said pole pieces and having a stylus carried therein, the opposite end of said armature device being confined between a pair of damping members for limiting the movement of said armature device under control of said stylus when said carrier is shifted to either extreme position for actuation of said stylus by either a hill and dale or a laterally cut phonograph record.

15. 11. In an electrical phonograph pick-up device, a supporting member, a carrier positioned on said member, a frame angularly movable with respect to said carrier, a permanent magnet system positioned on said frame, a pair of pole pieces carried thereby and directed toward each other, an electromagnetic winding, an armature device centrally located between said pole pieces and projecting through said electromagnetic winding, said armature device having a longitudinally extending shoulder thereon arranged to project into the adjacent faces of said pole pieces and to be resiliently suspended therein, a pair of limiting stops secured to the opposite ends of said pole pieces and directed toward each other for confining the movement of said armature device, said armature device being arranged to receive a stylus at the end thereof for actuation by

either a hill and dale or a laterally cut phonograph record when said frame is shifted to either extreme position.

In testimony whereof I affix my signature.

JOHN N. RAY.
